UNITED STATES PATENT OFFICE.

JOHN W. GRAHAM, OF HINTON, WEST VIRGINIA.

TYPOGRAPHICAL OR SLUG-CASTING MACHINE.

1,220,093.

Specification of Letters Patent. Patented Mar. 20, 1917.

Application filed July 23, 1915. Serial No. 41,572.

To all whom it may concern:

Be it known that I, JOHN W. GRAHAM, a citizen of the United States, residing at Hinton, in the county of Summers and State of West Virginia, have invented certain new and useful Improvements in Typographical or Slug-Casting Machines, of which the following is a specification.

My invention relates to typographical machines, such as linotypes of the original construction, wherein circulating matrices are released from a magazine in the order in which their characters are to appear in print, and then assembled in line together with expanding spacers, the composed line brought in contact with the face of a mold, the mold filled with molten metal to form a line of type or slug against the face of the matrices, which produce the type characters thereon, and the matrices thereafter returned to the magazine from which they were originally drawn.

More particularly it relates to that class of machines having a series of magazines, any one of which can be brought into operative position and locked therein, and wherein the magazines are removable and interchangeable.

My invention is embodied in the construction of the arms which guide the travel of the magazines, and in the construction of the locking device, but I do not claim the principle involved either in the housing of the magazines, the arms, or the mechanism which guides the travel of the magazines upward or downward, to be part of this invention, as they are claimed in previous applications filed by me. The main feature of this invention, is embodied in the feature whereby the series of magazines when brought to the lowest point of operative position, which brings the uppermost magazine into operative position, are then suspended in slotted arms. The guide rollers on the lower rack rest in the bottoms of the slots in the arms and the racks and magazines are thus suspended. A supporting base can now be lowered away from the racks and magazines, and the magazines and racks are so made as to be heavier behind than in front. As the base moves downward the racks and magazines can be brought to a substantially horizontal position to facilitate the quick and easy removal of the magazines.

In the accompanying drawings I have shown my invention as an example and in a preferred way, and many changes and variations may be made therein without departing from the spirit or principle of this invention, and I wish to be understood that I do not limit myself to any form, or embodiment, except in so far as such limitations are specified in the claims.

Referring to the drawings, Figure 1 is a side view of a portion of a linotype machine having my invention applied thereto. Fig. 2 is a rear view of the forked arm A. Figs. 3 and 3^A show top and side views of a rack and its magazine. Figs. 4 and 4^A show front and side views of the automatic lock.

Referring to Fig. 1—

A is the main forked arm of the machine.

A¹ is an arm extending back from the main arm A at each side to support the distributing mechanism.

A² is a brace at each side connecting the frame of the machine with the top of the arms A.

A³ shows the slots in the arms A.

A⁴ shows the holes in the arm A arranged in different vertical planes as shown to engage the lock pins.

B is the base which supports the magazines.

B¹ are the rollers in the base which allow the lowermost rack to move endwise on the said base.

B² shows the threaded nuts which engage the screws B³.

CC¹—²—³—⁴ and ⁵ are racks which support the magazines.

C¹ shows the guide rollers on the racks.

C² shows the supporting rollers on the racks.

C³ shows the stop dog in the said racks to hold the magazines in place (see Fig. 3).

D¹ shows the lock pins (see Fig. 4).

D² is the disk which supports the heads of the lock pins (see Fig. 4).

D³ is the shaft which operates the locking device.

D⁴ are universal joints in the shaft D³.

D⁵ shows a dial.

D⁶ shows a hand wheel having on it a finger D⁷.

E shows a hand wheel to raise and lower the magazines.

E¹ shows the shaft to operate the lowering and raising mechanism.

E² shows the cross shaft connecting the two screws B³.

M shows a magazine.

M¹ shows the extended ends of the 5 strengthening bars on the magazine M, which work in conjunction with the stop dogs C³ to hold the magazine in place.

In operating the machine the hand wheel E is turned to the right or left as desired, 10 and operates the shaft E² by intermeshed bevel gears. The shaft E¹ is connected to the screws B³ by intermeshed bevel gears, and the said screws are engaged with the nuts B² on the base B, thus raising or lowering the 15 magazines. To bring the magazines to a horizontal position, in order to remove a magazine or for any desired purpose, the base B is lowered until the guide rollers C¹ of the lowermost magazine rest on the bottom of the slots A³ in the arms A. The 20 base is then lowered sufficiently to allow the magazines to tilt backward to the desired angle. The magazines as ordinarily constructed are heavier at their rear than at 25 their frontal ends, and thus will tilt downward at the back by gravity. The arms A are made slotted to receive the guide rollers on the racks, and the said slots are made vertical above the operative position. Below 30 the operative position the slot runs back at an angle sufficient to allow the lowermost magazine, when resting with its guide rollers in the bottom of the slot, to tilt down at the back so as to rest on a line substantially 35 horizontal and still allow its frontal end to rise up without interfering with the escapement channel, and so that the other magazines of the series will also come to a horizontal position and not interfere with the 40 escapement channel.

No power raising or lowering device is shown on this machine, but it is obvious that any such device may be applied, such as any of the devices shown in the previous applications for patents on similar machines, by me. The entrance channel is hinged on a 45 slideable block and may be moved outward without changing its upright position, but this feature is no part of this invention, being 50 claimed in a previous application.

In operating the locking device the hand wheel D⁶ is turned to bring the finger D⁷ to the desired number on the dial D⁵. The dial D⁵ is numbered to correspond to the 55 number of magazines. The disk D² is made circular and the heads of the lock pins rest upon it. The disk has at a preferred point on its rim a depression large enough to receive the head of one pin. The pin whose 60 head is located above the said depression can drop into its corresponding hole A⁴ in the arm A when the base is moved to the proper position, but the other pins resting on the thicker parts of the disk D² are held 65 out and cannot engage their corresponding

holes. The pins are set in the base preferably in the form of a half circle and the holes in the arm A are set staggered across the said arm so as to be in line vertically each with its corresponding pin. The shaft 70 D³ is made preferably telescoped so that it can lengthen and shorten as the base moves up or down, and the said shaft is made with flexible joints. The lock pins D¹ are pressed in by any desired spring mechanism. 75

Having described my invention, its construction and operation, what I claim and desire to secure by Letters Patent of the United States, is as follows:

1. In a typographical machine the combination of a plurality of movable magazines, 80 racks in which the magazines are housed, guide members fitted to said racks, and a pair of slotted guide arms engaged by said guide members on the racks, said slots being vertical above the operative position and extending downwardly and backwardly therefrom.

2. In a typographical machine the combination of a plurality of movable magazines, 90 racks in which the magazines are housed, guide members fitted to said racks, a pair of slotted guide arms engaged by said guide members on the racks, said slots being vertical above the operative position and below 95 the operative position extending downwardly and backwardly at an angle for a specified purpose, a base shiftable relative to said arms and normally supporting the racks, and means to shift said base. 100

3. In a typographical machine the combination of a plurality of movable magazines, 105 racks in which the magazines are housed, guide rollers fitted to said racks, a pair of slotted guide arms to receive said guide rollers on the racks, said slots being vertical above the operative position and extending rearwardly below the operative position, a base shiftable relative to said slotted arms and normally supporting the racks and magazines, means to shift said base, and means to support the racks and magazines in the guide arms independent of the said base. 110

4. In a typographical machine the combination of a plurality of movable magazines, 115 racks in which the magazines are housed, guide rollers fitted to the said racks, a pair of slotted guide arms to engage said guide rollers on the racks, said slots being vertical above the operative position and extending backwardly at an angle therefrom, a base shiftable on said arms and normally supporting the racks and magazines, means to shift the said base, means to support the 120 racks and magazines in the slots of the guide arms independent of the said base, and means to tilt the magazines by shifting said base. 125

5. In a typographical machine the com- 130

bination of a plurality of movable magazines, racks in which the magazines are housed, guides fitted to the said racks, a pair of guide arms engaged by said guides on the racks, said guide arms being vertical above the operative position and below the operative position, being made with a backward angle.

6. In a typographical machine the combination of a plurality of movable magazines, racks in which the magazines are housed, guides fitted to the said racks, a pair of guide arms engaged by said guides on the racks, said guide arms being vertical above the operative position and below the operative position being made with a backward angle, a base shiftable on said arms and normally supporting the racks and magazines, means to shift the said base, and means to support the racks and magazines on the guide arms independent of the said base.

7. In a typographical machine the combination of a plurality of movable magazines, racks in which the magazines are housed, guides fitted to the said racks, a pair of guide arms engaged by said guides on the racks, said guide arms being vertical above the operative position and below the operative position being made with a backward angle, a base shiftable on said arms and normally supporting the racks and magazines, means to shift the said base, means to support the racks and magazines on the guide arms independent of the said base, means to automatically tilt the magazines by shifting said base, and means whereby the magazines, in tilting and in shifting automatically change their positions one relative to the other.

8. In a typographical machine the combination of a plurality of movable magazines, racks in which the magazines are housed, guides fitted to said racks, a pair of guide arms engaged by said guides on the racks, there being socket holes in said arms, a base shiftable relative to said arms, there being holes in said base to correspond vertically with the socket holes in the arms, and lock pins set in said holes in the base and engageable singly with the corresponding socket holes in the arms.

9. In a typographical machine the combination of a plurality of movable magazines, racks in which the magazines are housed, guide rollers on said racks, a pair of guide arms engaged by said rollers on the racks, there being socket holes in said arms, a base shiftable relative to said arms, there being holes in said base to correspond with the socket holes in the arms, lock pins set in said holes in the base and engageable with the corresponding socket holes in the arms, a disk having a depression revoluble under the heads of the said lock pins, and

means whereby said depression in the disk may be brought to rest under the head of any desired pin.

10. In a typographical machine the combination of a plurality of movable magazines, racks in which the magazines are housed, a pair of guide arms engaged by said racks, there being socket holes in said arms, a base shiftable relative to said arms, there being holes in the said base to correspond vertically with the socket holes in the arms, and lock pins set in the said holes in the base and engageable with the corresponding socket.

11. In a typographical machine the combination of a plurality of movable magazines, racks in which the magazines are housed, a pair of guide arms engaged by said racks, there being socket holes in said arms, a base shiftable relative to said arms, there being holes in the said base to correspond vertically with the socket holes in the arms, lock pins set in the said holes in the base and engageable with the corresponding socket holes in the arms, a disk revoluble under the heads of the said lock pins, there being a depression in the said disk, and means whereby the said depression in the disk may be brought to rest under the head of any desired pin.

12. In a typographical machine the combination of a plurality of movable magazines, racks in which the magazines are housed, a pair of guide arms engaged by said racks, there being socket holes in said arms, a base shiftable relative to said arms, there being holes in the said base to correspond vertically with the socket holes in the arms, lock pins set in the said holes in the base and engageable with the corresponding socket holes in the arms, a disk revoluble under the heads of the said lock pins, there being a depression in the said disk, means whereby the said depression in the disk may be brought to rest under the head of any desired pin, a dial numbered to correspond with the magazines, and a hand wheel carrying a designating finger on the said dial.

13. In a typographical machine the combination of a plurality of movable magazines, racks in which the magazines are housed, a pair of guide arms engaged by said racks, there being socket holes in said arms, a base shiftable relative to said arms, there being holes in the said base to correspond vertically with the socket holes in the arms, lock pins set in the said holes in the base and engaging with the corresponding socket holes in the arms, a disk revoluble under the heads of the said lock pins, there being a depression in the said disk, means whereby the said depression in the disk may be brought to rest under the head of any desired pin, a dial numbered to correspond with the magazines, a hand wheel carrying a

designating finger on the said dial, a telescopic shaft with flexible joints connecting said hand wheel and the disk, and means whereby the number designated by the said 5 finger corresponds with the number of the lock pin occupying the depression in the said disk.

14. In a typographical machine the combination of a plurality of movable magazines, 10 racks in which the magazines are housed, guide arms for said racks, there being socket holes in said arms, a shiftable base, there being holes in said base to correspond with the socket holes in the said arms, lock pins 15 set in said holes in the base and engageable with the corresponding socket holes in the arms, a disk having a depression revolvable under the heads of the said lock pins, means whereby said depression may be brought to

rest under the head of any desired pin, a dial 20 numbered to correspond with the magazines, a designating finger adjacent said dial, a telescopic shaft with flexible joints connecting said finger and disk, means whereby the number designated by said finger corre- 25 sponds with the number of the lock pin, disposed in the depression in said disk, and means whereby any desired magazine whose number is designated on the dial will be automatically locked when brought into op- 30 erative position.

In testimony whereof I affix my signature in presence of two witnesses.

JOHN W. GRAHAM.
